US00D782327S

(12) **United States Design Patent** (10) **Patent No.:** **US D782,327 S**
(45) **Date of Patent:** **** Mar. 28, 2017**

(54) **PACKAGING**

(71) Applicant: **Apple Inc.**, Cupertino, CA (US)

(72) Inventors: **Jody Akana**, San Francisco, CA (US); **Bartley K. Andre**, Palo Alto, CA (US); **Shota Aoyagi**, San Francisco, CA (US); **Jeremy Bataillou**, San Francisco, CA (US); **Daniel J. Coster**, San Francisco, CA (US); **Daniele De Iuliis**, San Francisco, CA (US); **M. Evans**, **Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Shin Nishibori**, Kailua, HI (US); **Matthew Dean Rohrbach**, San Francisco, CA (US); **Peter Russell-Clarke**, San Francisco, CA (US); **Mikael Silvanto**, San Francisco, CA (US); **Christopher J. Stringer**, Woodside, CA (US); **Eugene Antony Whang**, San Francisco, CA (US); **Rico Zörkendorfer**, San Francisco, CA (US)

(73) Assignee: **Apple Inc.**, Cupertino, CA (US)

(**) Term: **15 Years**

(21) Appl. No.: **29/546,675**

(22) Filed: **Nov. 24, 2015**

Related U.S. Application Data

(63) Continuation of application No. 29/489,065, filed on Apr. 25, 2014, now Pat. No. Des. 744,855, which is (Continued)

Primary Examiner — Derrick Holland

Assistant Examiner — Lauren Calve

(74) *Attorney, Agent, or Firm* — Sterne, Kessler, Goldstein & Fox P.L.L.C.

(57) **CLAIM**

The ornamental design for packaging, as shown and described.

DESCRIPTION

FIG. 1 is a perspective view of packaging showing our new design;

FIG. 2 is a front view thereof;

FIG. 3 is a rear view thereof;

FIG. 4 is a top view thereof;

FIG. 5 is a bottom view thereof;

FIG. 6 is a left side view thereof; and,

FIG. 7 is a right side view thereof.

The dashed broken lines in the Figures show portions of the packaging or environment that form no part of the claimed design.

The dot-dash broken lines in the figures show boundaries of the claimed design and form no part thereof.

1 Claim, 5 Drawing Sheets

Related U.S. Application Data

a continuation of application No. 29/431,882, filed on Sep. 12, 2012, now Pat. No. Des. 704,072.
